UNITED STATES PATENT OFFICE.

CLINTON ADOLPH SUEL HANSON, OF BARRON, WISCONSIN.

MULTICYLINDER FOUR-CYCLE EXPLOSION-ENGINE.

1,391,473.

Specification of Letters Patent. Patented Sept. 20, 1921.

Application filed May 2, 1919. Serial No. 294,184.

To all whom it may concern:

Be it known that I, CLINTON ADOLPH SUEL HANSON, a citizen of the United States, residing at Barron, in the county of Barron 5 and State of Wisconsin, have invented a new and useful Multicylinder Four-Cycle Explosion-Engine, of which the following is a specification.

This invention has reference to multi-cylinder four cycle explosion engines, wherein governing of the engine is on the hit-and-miss principle, and its object is to provide means whereby, during the governing period, an explosive charge is maintained in 10 the cylinders ready for firing as soon as the governing period ends. This is advantageous in that, during the entire governing period, the charge is maintained in a highly gaseous condition and makes up, in whole 15 or in part, the first charge to be fired in the multi-cylinder engine after the governing period. The arrangement is such that not only is the explosive charge greatly agitated and thereby rendered more highly efficient, 20 but there is no waste of fuel or loss of power due to a number of successive compressions.

In accordance with the invention a by-pass is provided between two cylinders of a twin cylinder engine, or between the cylinders of each pair in an engine having two or more pairs of cylinders. The arrangement may be so timed that the valve or valves controlling the by-pass are open at substantially the time when one cylinder of 35 a pair has just finished the intake of a charge and its mate has finished the exhaust, and the closing of the valves is caused a certain number of cycles later, say four or eight cycles, so that the firing operations are 40 resumed with the pistons in the same relative positions that they ceased to act. During the time that no firing occurs the charge is pumped back and forth between the two cylinders, thus preparing it for instant 45 firing.

The invention is particularly adapted to having the by-pass or transfer passage partly or wholly surrounded by the exhaust pipe or duct, thereby preventing the cooling 50 of the charge which is characteristic of the hit-and-miss type of governing. Because of these features, an engine equipped with the invention may successfully use heavy fuels like kerosene, even on light loads, and the 55 fewer explosions that occur in a given time mean a greater number of transfers from

one cylinder to the other, whereby the fuel is heated to an advantageous temperature and the fuel and air of the charge are thoroughly intermixed.

The invention will be best understood from a consideration of the following detailed description taken in connection with the accompanying drawing forming part of this specification, with the understanding, 60 however, that the invention is not confined to any strict conformity with the showing of the drawing, but may be changed and modified so long as such changes and modifications mark no material departure from the 65 salient features of the invention as expressed in the appended claims.

In the drawing:—

Figure 1 is a vertical section through an upright engine of the hit-and-miss type and 75 having the invention applied.

Fig. 2 is a more or less schematic view showing the hit-and-miss governor and associated parts.

Referring to the drawing, there is shown 80 an explosion engine A having twin cylinders 1 and 2. The engine is shown as of the upright type and is therefore provided with a base 3, but it is to be understood that the engine may equally as well be of the 85 horizontal type. While the engine is shown as provided with twin cylinders it is to be understood that four, or six, or more cylinders arranged in pairs, may be employed. Since the operation of the engine is substantially the same whether the cylinders be 90 two cylinders or multiple of two, in the following description it will be considered that the engine has but a single pair of cylinders. Within the cylinders 1 and 2 are pistons 4 95 and 5 of customary type and these pistons are connected by piston rods 6 to the cranks 7 of a crank shaft 8 suitably journaled in the base 3. Mounted on the crank shaft 8 are fly wheels 9. The engine is shown as provided with a cylinder head 10 in which are intake and exhaust ports 11 and 12 respectively, but as these features do not form part of the invention no particular showing or description thereof is deemed necessary. 105 The ports 11 and 12 are provided with intake valves 13 and exhaust valves 14 which may be of the customary character.

Opening into the cylinders 1 and 2, in the explosion chamber ends thereof, are ports 110 15, 16 respectively, and these ports are joined by a duct 17 through which one port com-

municates with the other, the duct having no other outlet than the ports 15 and 16. The passage of fluid through the duct 17 is controlled by valves 18 and 19 respectively. 5 These valves may be of the self-closing type and hence are each provided with a spring 20 for the purpose, said springs surrounding the valve stems 21 of the valves 15 and 16. Both valves may be under the control of a 10 bridge piece 22 carried by a lever 23 suitably mounted, say on the cylinder head 10, and this lever, at the end remote from the bridge piece 22, is connected to a push rod 24 extending through a guide 25 on a bracket 26 which may be cast or secured on 15 one of the cylinders of the engine or on some part of the frame of the engine.

In the particular showing of the drawing, the crank shaft 8 carries a pinion 27 meshing with a gear wheel 28 suitably mounted on the engine and in turn carrying a cam 29 provided with a cam recess 29^a. The bracket 26 is shown as provided with a journal bearing 30 carrying a shaft 31, on one end of which there is secured a pinion 32 meshing with the gear wheel 28, while the other end of the shaft carries a collar 33 with diametrically opposite posts 34 thereon. In each post 34 there is journaled an angle arm 35 terminating at one end in a ball or weight 36 and at the other end in an angle extension 37. The two extensions 37 are pivoted to a rod 38 extending through the shaft 31 and slidingly connected to the push rod 24. In the path of the end of the rod 24 adjacent to the rod 38 there is a nose projection 39 into and out of the path of which the push rod 24 is movable by the rod 38, which latter is under 40 the control of the levers 35 and weights 36, the latter being connected together by a spring 40 or other yieldable device. The nose 39 is carried by a slide 41 mounted for reciprocation through a bearing 42 carried 45 by a bracket 43 made fast to the engine frame. At the end of the slide 41 remote from the nose 39 there is a friction roller 44 in position to bear upon the cam 29, a spring 45 on the slide 41 tending to urge the 50 roller 44 continually against the cam 29.

The balls or weights 36 being carried by the shaft 31 rotate therewith when the engine is running and serve as a centrifugal governor, and the gearing, governor, slide 55 41 with its nose 39 and the push rod 24 constitute a hit-and-miss governing structure, in turn controlling the valves 18 and 19.

When the engine is running, and particularly when running at a speed above the normal speed of the engine, the weights 36 spread apart in opposition to the spring 40 and thereby draw the end of the push rod 24 adjacent to the governor into the path of the nose 39. On the next forward movement of 60 the slide 41 the end of the push rod 24, then

in the path of the nose 39, is engaged and the valves 18 and 19 are opened, whereby the interiors of the cylinders are placed in communication so that, assuming that one piston, say the piston 5, has completed or 70 about completed the intake stroke, and the other piston, say the piston 4, has about completed the scavenging stroke, the next forward movement of the piston 4 will not draw in a fresh charge by the regular intake 75 valve but will draw in through the duct 17 the charge already in the cylinder 2. As the reciprocations of the pistons continue, the charge originally drawn in by the piston 5 passes back and forth between the cylinders 80 1 and 2, because of the easy path for gases thus provided. This agitates the charge, thereby causing a very thorough mixture and also very thoroughly atomizing and 85 gasifying the fuel of the charge. The surging of the gases between the two cylinders continues so long as the speed of the engine is high enough to hold the nose 39 in engagement with the push rod 24, with the consequent holding open of the valves 18 90 and 19. The momentary dropping of the roller 41 into the notch 29^a is of no moment, since the very brief closing of the valves 18 and 19, if it occurs at all, has no appreciable effect, since by far the greater part of the 95 rotation of the cam 29 holds the valves 18 and 19 open. As soon as the speed drops the action of the governor is to move the push rod 24 out of the path of the nose 39, whereupon, the push rod being no longer held by the nose 39 returns to its first 100 position under the action of the springs 20 and the valves 18 and 19 are closed, thereby shutting off communication between the two cylinders, whereupon, the 105 next stroke of one of the pistons constitutes the compression stroke, and the charge being in an ideal condition for firing, is ignited and an explosion takes place to be followed by other explosions in the regular course of running of the engine. 110

The hit-and-miss governor shown in the drawing is to be taken as indicative of any hit-and-miss governor without limitation to the particular structure illustrated. In a 115 multi-cylinder four cycle engine of the hit-and-miss type, when one piston of a pair is moving toward the crank shaft its mate is moving away from the crank shaft, whether the cylinders of a pair be arranged side by side or in tandem, or otherwise.

The movement of the governor is so timed that when the governing period ceases and the transfer valves are closed the engine will resume operations of firing with the pistons 125 in practically the same relative positions they were at the beginning of the governing period. The exhaust valve operating means need not differ from the usual form except that they may be arranged to remain in the 130

inoperative closed position when the transfer valves are in the open position. When electric ignition is employed the hit-and-miss governor may be arranged to break the 5 circuit while the transfer valves are open.

In order to accomplish the breaking of the circuit, which may be considered as including the ordinary electric ignition system, not shown in the drawings, there is provided 10 a contact 45 (see Fig. 2,) carried by that part of the engine supporting the arm 23, and the latter is provided with a contact terminal 46. The contact 45 is suitably insulated, and supported by a clamp 45^a. The 15 arm or lever 23 carries the contact 46 into and out of engagement with the contact 45, and one lead 47 of the ignition circuit is attached to the contact 45, while the other lead 48 may be secured to any desired part of the 20 frame of the engine 1, say, for instance, the head 10, shown in Fig. 2.

When the engine is running, and the speed of the engine is such that the hit-and-miss governor is out of commission, the contacts 25 45 and 46 are in engagement, where they remain until excessive speed is reached, whereupon the push rod 24 is brought into the path of the nose 39, and the bypass 17 is again opened, whereupon the hit-and-miss 30 governor again functions, and at the same time breaks the ignition circuit between the terminal leads 47 and 48. The breakage of the circuit is maintained so long as the bypass 17 remains open despite a momentary 35 closing of the valves due to the dropping of the roller 44 into the recess 29^a. When, however, the speed of the engine has dropped and the projection 39 is moved out of the path of the rod 24, the valves 18 and 19 are 40 permitted to close, thus closing the bypass 17, and the contacts 45 and 46 are brought together, thus permitting the normal operation of the ignition circuit and the normal 45 action of the engine.

Various adjustments may be made so that the amount of charge in a pair of cylinders, when the transfer valves close, may be regulated so that one cylinder may have a full 50 charge and the other practically none, up to a position where both cylinders may have practically equal charges.

With the invention, one disadvantage of the hit-and-miss type of governing explosion engines is avoided in that the cylinders 55 do not become cool while the hit-and-miss governor is operating, as is the case with other hit-and-miss types of governors which operate by opening the exhaust valve to the atmosphere, whereby air at atmospheric 60 temperature is pumped into and out of the cylinders. With the invention such condition does not occur, since the same charge passes back and forth between the cylinders and the heat of the cylinders is thereby 65 conserved, warming up the charge to an ad-

vantageous temperature. Because of the fact that the charge is kept in the cylinders during the governing period, it is maintained in a highly vaporized condition by the transferring action and is therefore sure 70 to fire when the governing period ceases. Moreover, heavy fuels, like kerosene, may be successfully used in the hit-and-miss type of engines even on light loads, since the fewer the number of explosions which takes 75 place in a given time the greater is the number of transfers between the cylinders.

What is claimed is:—

1. A multi-cylinder explosion engine having means for establishing communication 80 between the interiors of the cylinders, and a hit-and-miss governor for opening said means of communication during the governing period.

2. A hit-and-miss multi-cylinder explosion engine having inlet and exhaust valves for each cylinder, means other than the said valves for establishing communication between the interiors of the cylinders, and means under the control of the hit-and-miss 90 governor for opening said means of communication during the governing period.

3. A hit-and-miss multi-cylinder explosion engine provided with means distinct from the valves for placing the explosion 95 chambers of the cylinders in communication and the governor timed in action to cause the connection of the cylinders when one of the cylinders contains an explosive charge, whereby, during the governing period, the 100 charge is caused to surge back and forth between the cylinders.

4. A multi-cylinder hit-and-miss governed explosion engine provided with inlet and exhaust valves and with a duct 105 between the cylinders through which the latter may communicate, and valve means for the duct controlled by the governor to open during the governing period.

5. A multi-cylinder hit-and-miss governed explosion engine provided with inlet and exhaust valves and with a duct between the cylinders through which the latter may communicate, and valve means for the duct 115 controlled by the governor to open during the governing period, said valve means and governor being timed to open communication between the cylinders when there is an explosive charge therein.

6. An explosion engine comprising a pair 120 of power cylinders having inlet and exhaust valves and normally closed means of communication therebetween and with the pistons in the cylinders reciprocating in alternation, and a hit-and-miss governor for the 125 normally closed means rendered active by the attainment by the engine of a speed above a predetermined limit, to open the means of communication for the surging of the contents of the cylinders back and forth 130

1
between them so long as the means of communication are open.

7. A multi-cylinder explosion engine comprising a pair of associated cylinders, with 5 a duct extending between and opening at the ends into the explosion chambers of the respective cylinders, whereby to provide communication between the cylinders, valves at the ends of the duct and movable simultaneously from a normally closed to an open 10 position and vice versa, and a hit-and-miss governor controlled by the engine and in turn controlling the valves, whereby the duct is closed while the speed of the engine 15 is below a predetermined minimum and the valves are opened to place the cylinders in communication on the engine attaining a supernormal speed.

8. A multi-cylinder explosion engine comprising a pair of cylinders provided with a 20 duct leading between the explosion chamber ends of the cylinders and opening at the

ends into said cylinders and there provided with valve seats, a valve at each end of the duct, other valves communicating with each 25 cylinder and constituting the intake and exhaust valves of the cylinders, and a hit-and-miss governor connected to and simultaneously controlling the valves at the ends of the duct and operative on the attainment of 30 the engine to a predetermined maximum speed, whereby to then open the duct to place the cylinders in free communication for the surging back and forth into and out of the cylinders through the duct of an explosive charge. 35

In testimony, that I claim the foregoing as my own, I have hereto affixed my signature.

CLINTON ADOLPH SUEL HANSON.
